FREQUENCY CONVERTING RADIO-
RECEIVER

Ralph D. Wyckoff, Ponca City, Okla.

Application December 19, 1928
Serial No. 327,157

2 Claims. (Cl. 250—20)

My invention relates to methods and apparatus used for frequency conversion, particularly as applied to radio receiving equipment, and has for its object the simplification of the apparatus together with improvement in the operating characteristics of the receiver.

It is well known that frequency converters as used in the radio art are made up of two components, an oscillator, and a modulator or mixing device so related that for an incoming signal of given frequency the local oscillator is adjusted to a frequency such as to produce beats of the desired frequency against the incoming oscillations and it is the purpose of the modulator or mixing device to produce in its output circuits this desired beat frequency.

Thus the well known superheterodyne receiver is made up of the following components. A frequency converter, an intermediate radio-frequency amplifier tuned to a fixed frequency and a demodulator or detector from the output circuits of which the audio-frequency signals are derived. The frequency converter, composed of the oscillator and modulator components, has for its purpose the changing of the incoming oscillations to the frequency for which the intermediate radio-frequency amplifier is tuned, the signal is there amplified at the converted frequency, demodulated in the following detector unit and audio-frequency components of the signal obtained.

As usually constructed the frequency converter requires the use of one three-electrode thermionic tube as an oscillator and another in the modulator unit often called the first-detector unit, or if preferred the oscillator and modulator functions may be combined in a single unit using a single three-electrode thermionic tube. In the use of a single three-electrode thermionic tube as a combination unit it is necessary to use some harmonic component of the oscillator-frequency to beat against the signal-frequency in order that the signal-frequency circuits and the oscillator circuits may be independently adjusted and function independently.

Instead of using the usual three-electrode tube I employ a four-electrode thermionic tube in the frequency converter unit. It is then possible to use the so-called dynatron characteristic of the tube to obtain oscillations of any desired frequency and simultaneously, by use of a fourth electrode of the tube, to modulate the oscillations so obtained by any other desired frequency and thus obtain in the output circuits the combination or beat frequency desired. Such opera-

tion of the four-electrode tube as a combination oscillator-modulator may be obtained which is equivalent to the use of two three-electrode tubes in that the adjustments of the component parts of the circuit may be made independent of one another and operation at a harmonic of the oscillator frequency is unnecessary.

It is also a well known fact that in the usual type of superheterodyne receiver the oscillator has a certain amount of coupling with the antenna circuits causing the antenna to radiate energy at the oscillator frequency or harmonics of it, a condition which causes interference with other nearby receivers. In order to eliminate such radiation from the receiver it has been the practice to couple the receiver to the antenna circuits through an additional three-electrode tube which functions as a signal-frequency amplifier ahead of the frequency converter. My use of the four-electrode thermionic tube in the frequency converter unit obviates the necessity for using any additional equipment to prevent radiation from the receiver since one of the electrodes of the tube effectively shields the oscillator electrodes from the antenna circuit electrode within the tube and it is only necessary to properly shield the two circuits external to the tube to prevent undesirable radiation.

In the accompanying drawing, Figure 1 shows the fundamental circuit whereby the dynatron characteristic of any three-electrode thermionic tube may be used to produce oscillations of any desired frequency. Figure 2 shows the same method applied to a four-electrode tube to produce the same result and in addition shows the use of the fourth electrode to modulate the oscillations so derived, at any desired frequency, thereby obtaining the desired frequency conversion. Figure 3 shows the fundamental circuits involved in the use of the four-electrode thermionic tube as the frequency converter unit in a superheterodyne type of receiver.

Referring to Figure 1, 1 is the cathode, 2 is the grid and 3 is the anode of a thermionic tube. Unit 5 is a tuned circuit in the anode circuit of the tube. If the anode potential and grid potential are properly adjusted, sustained oscillations may be produced in the anode circuit the frequency of which may be controlled by adjustment of the electrical constants of the anode circuit.

Referring to Figure 2, 4 is an additional grid element and 7 is an additional tuned circuit added to the circuit of Figure 1 and may be placed in the circuit of anode 3 as shown or in the circuit

of grid 2. If as mentioned above, the potentials of grid 2 and anode 3 are properly adjusted, sustained oscillations will be produced in the circuit of anode 3 which oscillations may be modulated at any desired frequency by means of generator 6 or other source of alternating potential suitably connected to grid 4. A tuned circuit or other selective filter 7 may then be introduced in the circuit of anode 3 or grid 2 and the resultant combination or beat-frequency may be obtained at the terminals of 7. If the electrical constants of circuit 7 are properly selected no parasitic oscillations at the frequency of circuit 7 will be generated, even though it is placed in the circuit of anode 3.

Referring to Figure 3, I have shown the fundamental circuit whereby the frequency converter shown in Figure 2 is applied to the well known superheterodyne type of radio receiver. Unit 6 is the coupling device that serves to apply the received signal frequency obtained from antenna system 10, which may be any of the usual type of collecting devices, to the grid 4. Oscillations in anode circuit 5 are thereby modulated by the signal-frequency and the derived or beat-frequency selected by filter 7 passed on to amplifier 8 which is the usual type of intermediate-frequency amplifier, thence to the demodulator 9 from which the audio-frequency components of the received signal are derived. Oscillator circuit 5 may be adjusted to produce any desired beat frequency thus the signal frequency may be converted to any frequency for which the filter and amplifier units 7 and 8 are adjusted. The signal-frequency circuit 6 may be independently adjusted to obtain maximum input to grid 4. The grid 4 may be given a suitable negative bias by means of cells 11 or other suitable source of biasing potential thereby reducing the damping effect of grid 4 on the tuned circuit 6 to a negligible amount. In addition, if circuit 7 is placed in the circuit of anode 3, the grid 2 may be so constructed as to effectively shield grid 4 from potential variations of anode 3, thereby preventing internal electrode coupling between the oscillating circuit 5 and the antenna circuits 6 and 10

and thus eliminating undesired radiation from the antenna device. Coupling between the oscillating circuit 5 and the antenna circuits external to the tube may easily be eliminated by the usual shielding devices.

It will be seen therefore that my use of the four-electrode thermionic tube as a frequency converter in the superheterodyne type of radio receiver allows the use of a single tube in the frequency converter unit without recourse to oscillator harmonics, makes possible the effective shielding of the antenna circuits from those of the oscillator thereby preventing undesirable radiation from the receiver, and improves the operating characteristics of the receiver.

What I claim is:

1. Frequency conversion apparatus comprising a negative resistance thermionic device comprising essentially a cathode, an inner control-grid, an intermediate or shield-grid, and an anode, an input coupling device in circuit between said inner grid and cathode, means for maintaining a suitable biasing potential on said inner grid, means for maintaining said intermediate or shield-grid at a positive potential with respect to all other elements of the thermionic tube, means for maintaining the anode at a positive potential intermediate to said shield-grid and cathode, said anode potential being of such value relative to the shield-grid that the anode exhibits negative resistance characteristics, an oscillatory circuit in said anode circuit, an output filter device in said anode circuit, whereby sustained oscillations produced in the anode circuit are modulated at the frequency impressed on the input grid and the resultant heterodyne frequency is available at the terminals of said output filter.

2. Frequency conversion apparatus as described in claim 1, wherein the input device of the grid circuit and the anode oscillatory circuit are tunable, permitting the input device to accommodate any input frequency and by adjustment of anode oscillatory circuit, maintaining the derived heterodyne frequency at any desired value, or at the frequency of the output filter device.
